UNITED STATES PATENT OFFICE.

JESSE H. SPROWLES, OF PHILADELPHIA, PENNSYLVANIA.

CIRCULAR-KNITTING MACHINE FOR MAKING OPEN OR LACE WORK.

SPECIFICATION forming part of Letters Patent No. 650,874, dated June 5, 1900.

Application filed November 6, 1899. Serial No. 735,872. (No model.)

To all whom it may concern:

Be it known that I, JESSE HORACE SPROWLES, a citizen of the United States, residing at Philadelphia, county of Philadelphia, and State 5 of Pennsylvania, have invented a new and useful Improvement in Manufacturing Open or Lace Work on a Circular-Knitting Machine, of which the following is a full, clear, and exact description, reference being had to the accompanying drawings, which form a part of this specification.

I will first describe the mechanism for carrying out my invention illustrated in the accompanying drawings, in which—

15 Figure 1 is a partial side elevation of the knitting machine embodying my improvement. Fig. 2 is a detail view of the cam for controlling the needles. Fig. 3 is a section through the needle-cylinder. Fig. 4 is a plan 20 view of the needle-lifting mechanism, and Fig. 5 is an enlarged view of the portion of the fabric manufactured by my improved machine.

From an examination of the fabric it may be seen that the open-work is formed in the 25 following manner, each section of the open-work consisting of the following: a series of wales, then the omitted wale, then a wale in which the stitches are alternately formed, and so in every alternating round a stitch is 30 formed. Then follows the omitted wale, and then series of wales. As may be seen, the fabric thus produced has the appearance of lace-work, having the central longitudinal 35 thread or lock-stitch and a set of double wales on each side of the central portion, the thread passing or floating from each side of this central portion to the double wales. I produce this fabric upon a circular-knitting machine, and I produce it on a circular-knitting 40 machine of the character which is illustrated in Letters Patent No. 538,518, dated April 30, 1895, issued to Harry A. Houseman. That machine, as is well known, consists of an operating cam-cylinder A, which is driven by the 45 gear B upon the shaft b, which shaft b is rotated by means of the bevel-gear C meshing into the bevel-gear c' on the driving-shaft D. The needles E are held in levers E' E². The levers E' control those needles which in the 50 manufacture of circular goods, such as stockings, are during the formation of the heel and toe thrown out of action. In the operation

of this machine, as is fully set out in the patent mentioned before, the levers E' are at a desired point in the knitting automatically 55 operated by means of the plate F to throw them out of action. In order to form open-work or lace fabric by this machine, I change the mechanism or connections of some of the levers E' in the following manner: Taking a 60 group of five levers, which will make one complete repeat of the lace-work, I connect the first two to the plate F in the ordinary manner. From the next lever the needle is removed. The tail of the next lever instead 65 of being connected directly to the plate F is connected to the plate F', which plate F' rests upon the plate F when the needle is in action. The needle from the next lever is removed. This completes a repeat of the 70 needles to form one repeat of the lace-work. The plate F' is connected to the rods G G', which rods G G' extend downwardly loosely through the plate F and are connected together at the bottom by the cross-piece G², 75 having a projecting portion g, which rests upon the cam H, having a high portion h and a low portion h'. This cam H is on the shaft I. This shaft I has a bevel-gear J, which meshes with the bevel-gear K on the shaft b. The 80 relation of the bevel-gears K and J are as one to two. The spring L is confined to hold the rods G G', and with them the plate F', down against the plate F. In one rotation of the cam H the rod will be elevated and depressed. The relation of the gears J and K 85 are as one to two. The cam H revolves once for every two revolutions of the machine, and thus the levers E', which are controlled by the cam, are alternately turned in and out 90 of action with the successive revolutions of the machine. By this operation it may be seen that so long as the machine is rotating, which is the only time in which I make lace-work, as in stockings, it would be undesirable 95 to make this lace-work in the heel and toe.

In a repeat two needles are at all times in action, the next needle is at all times out of action, the next needle alternately in and out of action, and the fifth at all times out of action. I do not intend to limit myself to this specific arrangement, as of course it might be varied without departing from my invention.

Having now fully described my invention,

what I claim, and desire to protect by Letters Patent, is—

1. In a circular-knitting machine, the combination with a needle and operating-lever for said needle, of a plate upon which the end of said lever rests, a rod connected to said plate, a rotary cam having low and high points upon which the other end of said rod rests, rotating mechanism for said machine and connection between said cam and the rotating mechanism adapted in its revolution to rotate said cam one half-revolution.
2. In a circular-knitting machine, the combination with a needle and operating-lever for said needle, of a plate upon which the end of said lever rests, a second plate upon which the first plate rests, a rod connected to the plate upon which the lever rests, said rod passing loosely through the second plate, a rotary cam having low and high points upon which the other end of said rod rests, rotating mechanism for said machine and connection between said cam and the rotary mechanism adapted in its revolution to rotate said cam one half-revolution.
3. In a circular-knitting machine, the combination with a plurality of needles operating-levers equal in number and corresponding to said needles, a plate upon which the ends of said levers rest, rods connected to said plate, a plate connected to the other end of

said rods, a rotary cam having high and low points, there being a projection on said last-mentioned plate resting upon said cam, rotating mechanism for said machine and connection between said cam and the rotating mechanism adapted in its revolution to rotate said cam one half-revolution.

4. In a circular-knitting machine, the combination with a plurality of needles, operating-levers equal in number and corresponding to said needles, a plate upon which the ends of said levers rest, a second plate upon which the first plate rests, rods connected to said first-mentioned plate, there being orifices in the second plate through which said rods pass, a plate connected to the other end of said rods, a rotary cam having high and low points, there being a projection on said last-mentioned plate resting upon said cam, rotating mechanism for said machine and connection between said cam and the rotating mechanism adapted in its revolution to rotate said cam one half-revolution.

In testimony of which invention I have hereunto set my hand, at Philadelphia, Pennsylvania, on this 3d day of November, 1899.

JESSE H. SPROWLES.
